UNITED STATES PATENT OFFICE.

ANDREW STROMDAHL, OF LYNN, MASSACHUSETTS.

SHOE-SEWING MACHINE.

1,177,972.

Specification of Letters Patent.

Patented Apr. 4, 1916.

Application filed October 8, 1914. Serial No. 865,731.

To all whom it may concern:

Be it known that I, ANDREW STROMDAHL, a citizen of the United States, and resident of Lynn, in the county of Essex and State of Massachusetts, have invented new and useful Improvements in Shoe-Sewing Machines, of which the following is a specification.

My invention relates to McKay shoe sewing machines, and consists in improvements by the aid of which the stitching mechanism operates more effectively than in the standard McKay machines heretofore used. In shoe stitching machines of this character, the work is placed upon the horn and rests upon a perforated plate at the tip of the horn, this plate serving as the work support by which the pressure of the presser foot is sustained. At the instant of the stitch cycle when the thread is being drawn up through the work, it has been necessary to relax the pressure of the presser foot so as to relieve the friction on the thread already engaged by the work, thus to enable the needle in rising to draw the stitch tightly into the shoe. Since the work possesses some flexibility the stitch is thus drawn under a disadvantage which would not be encountered if it had been practically possible to maintain the pressure of the presser foot during the drawing of the stitch. My improvements are characterized by a device which enables the pressure of the presser foot to be maintained upon the work until the stitch has been completely formed when the presser foot pressure may then be released only for such period in the stitch cycle as is necessary to allow the feed movement to take place. Under the conditions heretofore prevailing, it has also been the practice to start the feed movement of the work almost simultaneously with the release of the needle from the work itself so as to move that portion of the thread which is engaged by the last preceding stitch out of close contact with the supporting plate in the tip of the horn and by this means to improve the stitch so far as possible in respect to the tightness and firmness with which it is drawn into the work. For a portion of the stitch cycle therefore the needle in rising from the work to its uppermost position draws the thread at a disadvantage and at an increasing angle of obliquity to the perpendicular path in which the needle vibrates. My improvements make it possible to shorten the period

of work feed so that this need not take place until after the stitch has been entirely drawn and the needle has come practically to a position of rest at the upper limit of its movement.

In the drawings hereto annexed which illustrate my invention, Figure 1 is a vertical section of the horn of a McKay sewing machine with my improvements applied thereto; Fig. 2 is a top plan view on an enlarged scale of the tip of the horn; Fig. 3 is a plan view also on an enlarged scale of a gear plate forming part of the looper mechanism; Fig. 4 is a vertical sectional view on an enlarged scale of the tip of the horn with my improvements attached showing the relationship of my improvements to the formation of a stitch and the feeding of the work; Fig. 5 shows in plan and elevation the button which constitutes a characteristic element of my invention; Fig. 6 is a side elevation of the feed cam of a McKay machine showing the modifications therein which my improvements make possible; Fig. 7 is a face view of the presser foot operating cam of the machine showing modifications therein appropriate to my invention; and Fig. 8 shows in plan and elevation a modified form of button.

The general assemblage of my improved work supporting and thread guiding device is shown in Fig. 1. Therein A represents a portion of the framework of a McKay stitcher, and B the horn. The looper L is essentially of the usual characteristics and is rotatably mounted at the tip of the horn. The driving mechanism for the looper is however rearranged in order to supply the necessary accommodation for my improvements which relate to the thread guide and work support. The looper L which is provided with a spur gear annulus L' is rotated by means of idler gears L² and L³ which are rotatably mounted upon a plate L⁴, this plate being dovetail-secured into place near the tip of the horn. The idler L³ is a spur and crown gear which meshes with and is driven by the pinion M' formed in the end of the inclined shaft M. The remainder of the looper actuating mechanism is substantially the same as that which has long been in use and need not be described.

Instead of the usual fixed plate at the tip of the horn, I provide a rotatable button D shown individually in Fig. 5. The button D is centrally perforated at D³ and has a ra-

dial channel D^4 extending from the central perforation to the circumference. Below the top of the button there is formed the neck D^2 and below the neck D^2 the spur gear D' .

5 The button is secured in place by means of the projection G^7 (see Fig. 4) which lies between the top of the button and the projecting annulus formed by the gear teeth D' . The idler spur gear G meshes with the gear 10 D' and the idler G' in turn with the idler G . The idler G' is a spur and crown gear or spur and bevel gear which meshes with and is driven by the pinion G^3 formed on the end of the inclined shaft G^2 . At its lower end 15 shaft G^2 is provided with a gear G^4 which meshes with a similar gear G^5 on the vertical shaft G^6 . The latter shaft is secured to the spur gear C^2 at the base of the horn and this gear is controlled by the spur gear annulus C through the idler C' . The annulus C is fixed to the bed A of the machine and its gear ratio with the gear C^2 is determined so that no matter to what position the horn B may be turned, the button D at the tip of the 20 horn will remain stationary without rotation and the radial channel D^4 in the top of the button will always point in the direction of the work feed.

It will be perceived by reference to Fig. 4 30 that when the needle N , having penetrated the work S' and engaged a loop of the thread, and having then risen out of the work, that portion of the thread T which has been engaged in the work by the last 35 preceding stitch-formation will lie in the channel D^4 formed in the top of the button D and that consequently although the pressure of the presser foot P be maintained to hold the work firmly against the button D , 40 this pressure will not produce any friction or binding effect upon the thread. The needle N , therefore, coöperating with the usual thread tension (not shown) effectively exerts its pull upon the thread T and draws 45 the previously formed loop tightly into the work. The maintenance of the presser foot pressure upon the work enables the stitching mechanism to form the stitch and draw the loop much more effectively than is the case 50 when this pressure is relaxed as has been the practice heretofore. Under the conditions furnished by these improvements, there is no necessity for moving the work forward until after the needle has completed its full 55 upward movement, since the thread T is not in any way engaged or restrained by contact with the button D . In order to adapt the McKay machine completely to these improvements, and to give the improvements 60 full opportunity to accomplish their result, it is necessary to redesign the cams which control the presser foot and also the feed, particularly the former. In Fig. 6 which shows the feed controlling cam in the McKay machine, the existing design gives a

cam lift of considerable duration as shown by the dotted line F^2 on the cam F' . With my improvements above described and incorporated in the machine the feed movement may be delayed, and for this purpose the 70 cam should be redesigned so that the cam lift is represented by the cam outline at F^3 . Likewise, the presser foot controlling cam shown in Fig. 7, which heretofore has been designed as indicated by the dotted lines P^2 , 75 should be redesigned so that its throw is delayed and the duration thereof shortened, being controlled by the contour indicated at P^3 . As the relaxation or lift of the presser 80 P (Fig. 4) is substantially coterminous with the forward movement of the feed dog F , the redesigning of the two cams should be such that the timing, lift and throw of the two cams should correspond. Since under 85 the conditions supplied by these improvements the presser foot P does not relax its hold on the work until the needle has practically come to rest for the feed movement to begin, the labor of stitching shoes on a McKay machine is very materially lessened 90 since the machine itself does the work of holding the shoe firmly during all the active portions of the stitch cycle. In addition to this, as above indicated, these improvements enable the stitch to be formed more firmly 95 and with less wear on the thread or danger of breaking it.

The work-supporting and thread-guiding button, characterized by a thread channel in which the thread may be drawn without encountering friction by being nipped between the button and the shoe, is the foundation on which the improved results rest. The device of maintaining this button stationary in relation to the bed of the machine and 100 thus maintaining the thread channel fixed in position to coincide with the direction of work feed, is important, and constitutes part of my improvements in the preferred form shown in Figs. 1 to 7 inclusive. However, a 105 measurable proportion of the improvements and advantages above set forth may be secured with a work-supporting button made as illustrated in Fig. 8. This form of button has the central thread aperture D^3 as 110 usual, but the crown of the button is composed of a number of radial ridges D^5 , separated by radially disposed channels D^6 . The tops of the ridges D^5 are smoothed, and made as narrow as is consistent with the 115 proper feed movement of the work which rests and slides on the button. The button is held in place by means of the neck D^2 and a flange D^7 and is preferably loose and free to rotate in its seat at the end of the 120 horn. The thread T will find its way into any one of the channels D^6 , by slipping off the ridge D^5 , and when the button is as preferred, loosely and rotatably mounted, the 125 thread itself will turn the button so as to 130

maintain the thread containing channel in substantial coincidence with the direction of work feed. If the button does not turn freely, the thread will slip from one channel 5 D⁷ to the next. With this arrangement, the positive gear control of the button being eliminated, it will be advisable to moderate the presser foot pressure during the period while the thread is being drawn, so as to 10 guard against accidental nipping of the thread between the button and the work, and consequent breakage of thread. While this form of thread-channeled button may be employed, the gear-controlled button will 15 be found practically much the better.

I claim:

1. In a shoe sewing machine, the combination with the rotary horn, stitching mechanism, feed mechanism and presser foot, of 20 a button rotatably mounted in the horn and radially channeled on the side toward the work.
2. In a shoe sewing machine, the combination with the rotary horn, stitching mechanism, feed mechanism, presser foot and 25 presser foot actuating mechanism, of a button rotatably mounted in the horn and radially channeled on the side toward the work, the presser foot mechanism being timed to release pressure after the stitches are drawn into the work.
3. In a shoe sewing machine, the combination with the horn, stitching mechanism, feed mechanism and presser foot, of a but- 30

ton rotatably mounted in the horn, and a 35 gear train controlling the button to hold it stationary in relation to the direction of feed, said button provided with a thread channel on the side toward the work.

4. In a shoe sewing machine, the combination with the rotary horn, stitching mechanism, feed mechanism, and presser foot mechanism, of a button rotatably mounted in the horn, a gear train controlling the button to hold it stationary in relation to the direction of feed, said button provided with a 40 thread channel on the side toward the work, the presser foot mechanism being timed to release pressure after the stitches are drawn 45 into the work.

5. In a shoe sewing machine, the combination with the rotary horn, stitching mechanism, feed mechanism, and presser foot mechanism, of a button rotatably mounted in the horn, a gear train controlling the button to hold it stationary in relation to the direction of feed, said button provided with a 50 thread channel on the side toward the work, the presser foot mechanism and feed mechanism being timed to release pressure 55 and advance the work after the stitches are drawn into the work.

Signed by me at Boston, Massachusetts, this seventh day of October, 1914.

ANDREW STROMDAHL.
